Re. 17,408

UNITED STATES PATENT OFFICE.

EDWARD EMANUEL LINEHAN, OF ST. PAUL, MINNESOTA, ASSIGNOR TO VICTOR TALK-
ING MACHINE COMPANY, OF CAMDEN, NEW JERSEY, A CORPORATION OF NEW
JERSEY.

RADIO ATTACHMENT FOR PHONOGRAHS.

Original No. 1,516,745, dated November 25, 1924, Serial No. 629,358, filed April 2, 1923. Application
for reissue filed January 23, 1926. Serial No. 83,381.

My invention relates to improvements in
radio attachments for phonographs.

It has become common practice to employ
the sound amplifying horns of phonographs
5 to amplify sounds from the different radio re-
ceiving instruments. Some of the methods of
application of said instruments to phono-
graph horns involve the mutilation thereof
and the resultant sacrifice in the resonance of
10 the horn. Other methods of application re-
sult in rendering the usually artistic cabinets
unsightly in appearance and are often at-
tended with laborious manipulation required
15 to convert the phonograph mechanism for use
in connection with radio equipment and in
adapting it again to normal use.

An object of my invention is to provide a
simple attachment for phonographs, which is
easily applied thereto, without undesirably
20 affecting the artistic features thereof, and
which may be easily and quickly operated to
alternately adapt the phonograph amplifier
for use with the sound producing means of
the phonograph and with such means of an-
25 other device.

More specifically it is my object to provide,
in a device of the present nature, a movable
mounting common to the sound producing de-
vices of a phonograph and a radio receiving
30 set, the movement of said mounting serving to
selectively bring said devices into communica-
tion with the phonograph amplifier and
serving further, in either case, to modify the
volume of sound, as may be desired.

35 With the foregoing and other objects in
view, which will appear in the following de-
scription, the invention resides in the novel
combination and arrangement of parts and in
the details of construction hereinafter de-
40 scribed and claimed.

In the drawings, Fig. 1 is a diagrammatical
view in vertical, central section, illustrating a
conventional phonograph and my improved
attachment applied thereto; Figs. 2 and 3
45 are views illustrating a portion of the top of
the cabinet body and showing the converter
slide, in plan, in different positions and Fig.
4 is a vertical sectional view in detail taken
on the line 4—4 of Fig. 3.

50 Referring to the drawing, A indicates the
cabinet of a conventional phonograph, the
same having the ordinary sound amplifying
horn 10 registering at its receiving end with

an opening 11 in the head piece or motor
board 12. Instead of fixedly mounting the
55 usual hollow base 13 of the phonograph tone
arm on the head piece 12 in position covering
the opening 11, I supply a special mounting
therefor. This mounting comprises a plate or
slide 14 having beveled side edges slidably in-
60 terlocked with correspondingly beveled
guides 15. Said slide is formed with open-
ings 16 and 17 therethrough, the opening 16
being arranged to rest in full registration
with the opening 11 in the head piece 12 when
65 the slide 14 is moved to its extreme right pos-
ition (Figs. 3 and 4) with the right end there-
of against a stop or abutment 18.

The opening 17 in said slide is arranged to
fully register with said opening 11, when the
70 slide 14 occupies extreme left position (Figs.
1 and 2) with the left end thereof against a
stop or abutment 19. The base 13 of the tone
arm is mounted on the slide 14 so as to cover
the opening 17 and a loud speaking radio re-
75 ceiver 20 or other sound conducting instru-
ment is mounted on said slide so as to cover
the opening 16. In using the phonograph, the
slide 14 occupies the position shown in Figs. 1
and 2, wherein the tone arm of the phono-
80 graph is brought into communication with the
horn 10, said horn being converted to use in
connection with the radio speaker 20 by mere-
ly shifting the slide 14 to the right and there-
85 by bringing the radio instrument into com-
munication with said horn. Thus, it will be
understood that the user, by a simple thrust
of the slide 14, can employ the horn 10 as an
amplifier for the phonograph or for other as-
90 sociated sound reproducing means. It will
also be understood that adjustment of the
slide restricting registration of the openings
16 and 17 with the opening 11 will modify
the volume of sound issuing from the horn 10.

Changes in the specific form of my inven-
tion, as herein disclosed, may be made within
the scope of what is claimed without depart-
ing from the spirit of my invention.

What is claimed is:

1. The combination with a phonograph 100
including the usual amplifying horn and
hollow tone arm base and also with a radio
sound producing instrument, of a slide sup-
plying a mounting for said base and instru-
105 ment, said slide traversing the receiving end
of said horn and having openings there-

- through arranged to severally register with said end of said horn, one opening being in communication with said base and the other with said instrument.
5. 2. The combination with a phonograph including the usual amplifying horn and hollow tone arm base and also with a radio sound producing instrument, of a mounting for said base and instrument, said mounting having openings therethrough, one for communication with said base and one for communication with said instrument, the mounting being movable to selectively guide said openings into registration with the receiving end of said horn.
10. 3. The combination with a phonograph including the usual amplifying horn and hollow tone arm base and also with a radio sound producing instrument, of a mounting for said base and instrument, said mounting having openings therethrough, one for communication with said base and one for communication with said instrument, the mounting being movable to selectively guide said openings into registration with the receiving end of said horn and opposed abutments to stop said mounting in positions acquiring full registration of said openings with said end of said horn.
15. 4. The combination with a phonograph including its amplifying horn and tone arm and also with a radio sound producing instrument, of means mounting said tone arm and instrument for simultaneous movement whereby either said tone arm or said instrument may be moved into communication with said horn and the other moved out of communication with said horn.
20. 5. The combination with a phonograph including its amplifying horn and tone arm and also with a radio sound producing instrument, of a unitary support for said tone arm and said instrument, said support being movable to selectively bring either said tone arm or said instrument into communication with said horn.
25. 6. The combination with a phonograph including its amplifying horn and tone arm and also with a radio sound producing instrument, of a member movably mounted with respect to the amplifying horn and mechanically connected to move said tone arm and instrument whereby said tone arm and instrument may be selectively brought into communication with said horn by the movement of said member.
30. 7. In combination with a cabinet, a sound amplifier mounted on the cabinet, a sound conducting member, an electrical sound producing instrument, and a unitary support for said member and said instrument movably mounted on said cabinet, said support being movable rectilinearly to selectively bring said member or said instrument into operative relation with said amplifier.
35. 8. The combination with a phonograph, having an amplifying horn and a tone arm, and an electrical sound producing instrument, of a support for said tone arm and instrument, said support being rectilinearly movable to selectively bring either said tone arm or said instrument into communication with said horn.
40. 9. In combination, a cabinet, a sound amplifying horn immovably mounted on the cabinet, a member mounted on the cabinet, a sound conduit on said member, and an electrical sound producing instrument on said member, said member being movable to selectively bring either said sound conduit or said instrument into operative relation with said horn.
45. 10. The combination with a phonograph including a stationary amplifying horn and a movably mounted sound instrument and tone arm movably mounted above the motor board, of rectilinearly slidable means adapted to severally guide said tone arm and instrument into communication with said horn.

In testimony whereof I have signed this specification.

EDWARD EMANUEL LINEHAN.
